United States Patent Office

Des. 210,770
Patented Apr. 16, 1968

210,770

INSTRUMENT PANEL

Friedrich Geiger, Boblingen, and Karl Wilfert, Gerlinger-Waldstadt, Germany, assignors to Daimler-Benz Aktiengesellschaft of Stuttgart, Unterturkheim, Germany

Filed Mar. 2, 1964, Ser. No. 78,845

Claims priority, application Germany Sept. 4, 1963

Term of patent 14 years

(Cl. D14—3)

FIG. 3

FIGURE 1 is a front elevational view of the instrument panel embodying our novel design;

FIGURE 2 is a top plan view of the instrument panel of FIGURE 1; and

FIGURE 3 is a perspective of the instrument panel illustrated in FIGS. 1 and 2, it being understood the meter details which are shown in broken lines for ease of illustration are identical to the full line disclosure shown in FIG. 1.

We claim:

The ornamental design for an instrument panel, as shown and described.
